UNITED STATES PATENT OFFICE.

MARTINUS SIEVEKING, OF LAKE MAHOPAC, NEW YORK.

INTERNAL-COMBUSTION ENGINE.

1,252,045.

Specification of Letters Patent.

Patented Jan. 1, 1918.

Application filed August 14, 1917. Serial No. 186,164.

To all whom it may concern:

Be it known that I, MARTINUS SIEVEKING, a citizen of the Netherlands, and a resident of Lake Mahopac, in the county of Putnam 5 and State of New York, have invented a new and Improved Internal-Combustion Engine, of which the following is a full, clear, and exact description.

This invention relates to a two-cycle internal combustion engine and has for an object the provision of an engine in which the usual inlet valves are eliminated.

Another object in view is to provide an improved construction in two-cycle internal 15 combustion engines wherein compression cylinders are provided in lieu of inlet valves.

A still further object of the invention is to provide a structure having a divided cylinder having a plurality of explosion chambers with a piston in each chamber so that in 20 at least some of the chambers perfectly pure combustible matter may be positioned upon each compression so as to positively insure explosion on each revolution.

25 In the accompanying drawing:

Figure 1 is a longitudinal vertical section through an engine disclosing an embodiment of the invention.

Fig. 2 is a top plan view of the engine in 30 Fig. 1.

Fig. 3 is a view similar to Fig. 1 but disclosing a plurality of power cylinders.

Referring to the accompanying drawings by numerals, 1 indicates a casing in which 35 the crank shaft 2 is mounted, said shaft being supported by suitable bearings and carrying a fly wheel 3. Arranged in the upper part of casing 1 are cylinders 4 and 5, cylinder 4 being preferably provided with a water jacket while a cooling jacket is not necessary for cylinder 5. Bolted or otherwise secured to cylinder 5, or supported in any desired manner is a carbureter 6 having a pipe 7 communicating with the interior of 40 cylinder 5 at 8, thus producing an inlet for an explosive mixture. Connected with cylinder 5 and communicating with the interior thereof through the discharge port 9 is a pipe 10 which communicates with the interior of cylinder 4 through port 11. Cylinder 4 is divided by a partition member 12 so that two cylindrical chambers 13 and 14 may be provided for the pistons 15 and 16. Chambers 13 and 14 merge into a central chamber 17 at the top whereby a single spark plug 18 may be used for igniting the gas in 45 both the chambers 13 and 14. An outlet 19 is provided near the bottom of the chamber 14 and substantially in the same horizontal plane as the inlet 11. By this construction 50 and arrangement whenever the fresh gas or explosive mixtures enter the cylinder 4 chamber 13 is scavenged first and chamber 14 is scavenged last. It will also be noted that there is no remaining burnt gas in 55 chamber 13 and chamber 14 will have but little and that little adjacent the piston 16, whereby the spark plug 18 will be surrounded by perfectly good gas and thereby will produce an explosion at each revolution of 60 the engine. Two pistons and two chambers have been shown in the cylinder 4 but it will be evident that a greater number may be used if desired without departing from the spirit of the invention. A bifurcated or 65 yoked connecting rod 20 connects the pistons with the crank shaft 2 and the crank 21, while a straight connecting rod 22 connects the piston 23 in chamber 5 to the shaft 2 through crank 24. When the parts are in 70 the position shown in Fig. 1 the chambers 13 and 14 have just been scavenged and filled with an explosive mixture, and as the pistons 15 and 16 move upwardly ports 11 and 19 are closed and the explosive mixture is 75 compressed. Simultaneously with the upward movement of the pistons 15 and 16, piston 23 will move downwardly and thereby provide a rarefaction in the upper part 80 of the chamber and also in the pipe 10, so that as soon as the piston uncovers the port 8 the rarefaction or vacuum produced in the chamber will draw in a given quantity of 85 combustible mixture through the carbureter 6 which will properly mix and be later compressed as the piston 23 again moves upwardly as pistons 15 and 16 move downwardly on the explosion stroke. By the time the pistons 15 and 16 begin to uncover 90 ports 11 and 19 the power of the explosion has been absorbed and the compression in cylinder 5 has reached such a point as to quickly force the gas or explosive mixture 95 into the cylinder 4 where it is compressed and the process is repeated during the continued operation of the engine. It will be noted that the pistons 15 and 16 close the inlet and outlet ports during the compression 100 of the gas in the chambers 13 and 14 and chamber 17 and the rarefaction of the matter in cylinder 5 as well as the compression 105 of the gas therein before its discharge into 110

cylinder 4. The piston 23 may be made sufficiently long to continue to cover port 8 during its upstroke though preferably it is made somewhat shorter as shown in Fig. 1.

5 In Fig. 3 is seen a slightly modified form of the invention in which the same principle is used, but the casing 25 is made sufficiently large to accommodate a shaft 26 designed to be driven by two power cylinders 4' instead 10 of one as shown in Fig. 1, also there is provided two compression cylinders 5' with the carbureter 6 arranged therebetween and discharging into oppositely extending pipes 27 and 28. By this arrangement one compression cylinder 5' will be drawing in gas while the opposite one is compressing and consequently one cylinder 4' will be fired while the other is compressing. It is evident that any number of the units comprising cylinders 4' and 5' and associate parts could be 20 associated together and connected to one shaft. In all forms of the invention it will be seen inlet valves and outlet valves and all other valves are eliminated, unless the piston 23 and associate parts could be termed valves 25 as well as the pistons 15 and 16, as the last mentioned pistons close the ports during a certain part of the cycle of operation. It will also be noted that the only moving parts

are the pistons, the crank shaft and connecting parts.

What I claim is:

In an internal combustion engine of the character described, a power cylinder divided into a plurality of chambers, said cylinder having an inlet and an outlet port at one end, a piston for each of said chambers, said pistons closing said ports when compressing and during most of the power stroke, a compression cylinder having a 40 closed end, a carbureter connected with the compression cylinder at the end opposite the closed end, means for connecting the closed end of said compression cylinder with said inlet port, and means for connecting the piston of the compression cylinder and the pistons of the said chambers with the same crank shaft, said pistons being set one hundred and eighty degrees apart whereby the piston in the compression chamber will cause 50 a rarefaction in the closed end of the cylinder until the inlet to the carbureter has been uncovered and will then compress the charge from the carbureter until the completion of the power stroke of the pistons in the power 55 cylinder

M. SIEVEKING.
